UNITED STATES PATENT OFFICE.

SLOAN DANENHOWER, OF BRIDGEPORT, CONNECTICUT.

SIGNALING APPARATUS.

1,106,788.

Specification of Letters Patent. Patented Aug. 11, 1914.

Application filed July 3, 1912. Serial No. 707,526.

To all whom it may concern:

Be it known that I, SLOAN DANENHOWER, a citizen of the United States, at present residing at Bridgeport, in the county of Fairfield and State of Connecticut, have invented 5 certain new and useful Improvements in Signaling Apparatus, of which the following is a specification.

The invention relates to improvements in 10 signaling apparatus and is particularly designed for war or other vessels when operating in fleet maneuvers and its object is to provide an apparatus whereby signals may be automatically displayed simultaneously 15 with the commands given to the engineers in the engine room relative to the speed or the forward or astern movement of the ship.

The invention consists in certain novel 20 features of construction, combination and arrangement of parts as will be hereinafter fully described and claimed.

In the accompanying drawings, illustrating 25 the invention, in the several figures of which like parts are similarly designated, Figure 1 illustrates my invention installed upon a battleship. Fig. 2 is a vertical longitudinal section of one of the signals. Fig. 3 is a longitudinal section of the distributing or six-way valve and its operating handle and showing its connection with the 30 transmitter that is arranged on the bridge of the vessel and which is employed for despatching signals to the engine room, the transmitter being shown in elevation. Fig. 35 4 is a longitudinal section of the operating handle illustrating the air passages therein and the valve for controlling the flow of air through said passage. Fig. 5 is a face view of the outer face of the valve. Fig. 6 40 is a transverse section of the valve casing. Fig. 7 is a sectional elevation of one of the signals expanded.

In practice the signals are arranged in sets of three on either side of the vessel and are 45 suspended from one of the yardarms with the lower ends of their supports connected to the deck or bridge whereby to hold each set in longitudinal alinement and fairly rigid so as to prevent excessive swaying by 50 the wind or by the movement of the vessel. The signals now in use are made cone-shape and are run up on either side of the vessel by lines suspended from the ends of the yardarm, the present practice being to run 55 them up with their apexes up to denote the ahead movement of the vessel or with the

base of the cones up to denote the astern movement. The signals are known as "cones" when their apexes are pointed upwardly and as "tops" when the positions 60 are reversed.

In the drawings I show only one set of signals upon either side of the vessel, the signals upon one, the port side, when expanded having their apexes pointed upwardly and upon the other or starboard side with their "tops" or bases up. However in practice two sets of signals may be arranged upon each side of the vessel so that in maneuvering the vessels the signals may 70 be set to denote the direction of thrust or the speed of either the starboard or port propellers. However, when cruising at sea only one set of signals may be used as will be readily understood. 75

Each signal is substantially alike in construction and operation and I will therefore describe only one and will apply the corresponding reference characters to the several figures throughout the drawings. Each signal is constructed with a shaft 1 having an eye 2 at each end to each of which is connected a wire cable 3 by which the signals of each set are suspended in longitudinal alinement from one of the yardarms of the 80 vessel. The lower cable 3 is connected to the bridge or to the deck whereby to hold the signals fairly taut to prevent excessive swaying by the wind or by the movement of the vessel. 90

Upon the shaft 1 is mounted an air cylinder 5 in which operates a piston 6 having a central bore 7 through which the shaft freely passes. Extending from one end of the piston is a tubular piston rod 8 which surrounds the shaft 1 and which is extended through the upper end of the cylinder as shown. The lower end of the cylinder through which the shaft passes is provided with a stuffing-box and gland 9 to prevent 100 leakage of the air that is forced into the cylinder to operate the piston. To the outer end of the piston rod 8 is connected a double flanged ring 10 the upper flange of which is formed with open slots in which are held the lower ends of ribs 11 which are pivotally held upon a wire ring held between the flanges of the ring 10. To the outer ends of ribs 11 are pivoted the lower ends of ribs 12 whose upper ends are pivoted to a ring 13 110 that is securely held upon the upper end of the shaft and which is similar in con-

struction to the ring 10. A cover 14 of suitable material is arranged over the ribs 13 and connected thereto in any suitable manner. Surrounding the hollow piston rod 8 within the cylinder is an expansion spring 15 whose function is to normally hold the piston in the lower end of the cylinder and to return it thereto to close or collapse the signal when the pressure in the piston is released as will be hereinafter more fully described.

Compressed air is supplied to the cylinders 5 for operating the pistons to expand the signals through pipes 16 which are connected to the lower ends of the cylinders and which extend from a six-way distributing valve 17 mounted on the bridge of the vessel and which is operatively connected to the annunciator 18 employed for despatching signals to the engine room. The valve 17 is constructed with a casing 19 having air ports or passages 20 to each of which is connected one of the pipes 16 that extend to the cylinders 5. The ports 20 open through a valve seat 19' formed in the casing against which is rotatively held a valve 21 having a single port or passage 22 which extends rearwardly through one end of the stem 23 of the valve. The stem of the valve is rigidly connected to the pivotal end of a transmitter handle 24 carried by a support 18, and the said handle is provided with an air passage or channel 25 which communicates at one end with the air passage 22 and has its opposite end connected to a pipe 26 which extends from a suitable compressed air supply tank (not shown) carried by the vessel. The passage 25 extends upwardly through the handle from the port or passage 22 and thence downwardly therethrough to the pipe 26 and at the top of the handle the said passage is bisected by a valve socket 27 in which is held a spring seated valve 28 that controls the passage of air through the said channel. The valve 28 is formed with a stem 29 that extends upwardly through the end of the handle 24 so that it may be engaged by the thumb when the handle is grasped to operate the transmitter. The face of the valve 21 is formed with a segmental groove 30 which registers with all of the ports or passages 20 except the port with which the valve port 22 is in register. The groove 30 opens to the atmosphere through a port 31 arranged in the valve 21. By thus connecting the distributing valve with the transmitter handle it will be evident that the signals are operated simultaneously with the command given the engine room relative to the speed of the vessel.

Further understanding of the construction of the apparatus and its use will be best understood from the following description of its operation: As stated the signals are arranged in sets of three on either side of

the vessel and are operated according to the naval code to signal the other vessels of the fleet relative to the speed at which the vessels are to travel. We will assume that the fleet is starting on a cruise and as is customary, are traveling in column formation, the speed being governed by the flag-ship. The starting signal having been given the officer on the bridge of the flag-ship signals his engineer to start, we will say, at slow speed and as he throws the handle 24 over to transmit the command to the engine room the distributing valve will be correspondingly moved so that the port 22 will register with the port 20 leading to the lower cylinder 5 on the port side of the vessel, the stem 29 of the valve 28 is then pushed down which opens the passage 25 to allow the compressed air to rush into the lower end of the lower cylinder 5 thus elevating the piston 85 and opening or "setting" the lower signal. The valve 28 is then released thus trapping the air in the said cylinder and holding the signal open. When the speed is to be increased, we will say, to half speed, the transmitter handle is thrown over to its next position which rotates the valve 21 to cause its port 22 to register with the port 20 leading to the middle signal of the set which movement brings the groove 30 into register with the port 20 leading to the lower cylinder thus allowing the air to escape therefrom when the spring in said cylinder will force the piston to the lower end of its cylinder and thus collapse or close the signal. Then by operating the valves 28 as previously described air will be admitted to the second or middle cylinder to expand the signal. The same operation will be followed in setting the upper signal to indicate full speed ahead. By reversing the direction of throw of the handle the signals on the starboard side of the vessel may be operated to indicate the astern movement of the vessel.

It will thus be seen that I provide an exceedingly simple and efficient apparatus that may be readily set up or removed and by which signals may be transmitted to all the vessels of the fleet simultaneously with the command given the engineers of the vessels relative to the speed or the direction of thrust of the propellers without giving the command by word of mouth and the operation of the signals by hand. By arranging two sets of signals on either side of the vessel it will be apparent that signals may be given to run one propeller ahead and the other astern which is an advantage especially in maneuvering the ships when starting on a cruise.

As shown in Figs. 2 and 7 the signals are constructed with the ribs 11 shorter than the covered ribs 12 which latter are pivoted at their upper ends to a fixed ring so that when the signals are expanded they will take a

cone shape with their apexes arranged upwardly. However when the cones are inverted or have their "tops" down it will be understood that their shorter ribs 11 will be 5 pivotally held to the fixed ring and their longer covered ribs pivoted to the piston rod so that when expanded their tops will be down.

While I have shown the signals constructed to take a cone shape when expanded I do not wish to be limited to this form as it is evident that they may be constructed to take a spherical, semispherical or other shape as desired. Neither do I wish to be limited to 10 the arrangement or location of the distributing valve as it is obvious it may be detached from the transmitter and if desired a three-way valve may be employed for each 15 set of signals. It is also obvious that slight 20 changes may be made in the construction of the apparatus without departing from the scope of the invention.

What I claim is:—

1. The combination with a transmitting 25 handle having an air passage therein, means carried by said handle for controlling flow of air through said passage, of a series of visible signals, separate means for operating said signals, and a selective valve interposed 30 between said handle and said signal operating means, said selective valve being carried by and operatively connected with said handle.

2. The combination with a transmitting 35 handle, of a selective valve operating in unison with said handle, a series of visible pneumatically operated opening and closing signals, an air passage in said handle having communication with said selective 40 valve, and manually controlled means carried by said handle for admitting air to said valve for the purpose of opening the selected signal, the shifting of the position of said handle automatically exhausting air from 45 and closing all but the selected signal.

3. In combination with a transmitting handle, of a series of expansible signals, separate air controlled means for opening each signal, a selective valve operatively connected 50 to said handle and working in unison therewith, said valve cutting all but one of said signals out of operation at a time, and an operating means carried by said handle and controlling the opening of the remaining signal, said last mentioned signal being 55 released and automatically closed upon shifting the position of the handle.

4. A device of the kind described, comprising a plurality of expansible signals, an 60 air cylinder for each signal, a piston work-

ing in each cylinder, each piston being connected to one of said signals, a valve casing having air passages each of which is adapted to communicate with one of said cylinders, a valve working in the casing, an air 65 supply passage in said valve adapted to register successively with the casing passages, a handle operatively connected to said valve and having an air passage in communication with said valve passage, a hand controlled 70 valve controlling passage of air through said handle, and a source of air supply in constant communication with said handle, said valve having an exhaust passage which registers with all of said passages of the valve 75 casing except the one with which the supply passage of the said valve registers with.

5. A device of the kind described, comprising a plurality of signals, separate pneumatically operated means for operating said 80 signals, a transmitting handle having an air passage, a manually operated valve controlling the passage of air through said handle, and a selective valve controlling the operating means of said signals, the said 85 valve being carried by and operated in unison with said transmitting handle and adapted to receive air under pressure to be transmitted to the signal operating means through said handle, as and for the purpose set forth.

6. A signaling apparatus, comprising a support, an expansible signal connected at one end of said support, an air cylinder carried by the support, a piston working in 95 said cylinder and slidingly held on said support and having a hollow piston rod surrounding said support connected to said signal, means to supply air under pressure to said cylinder, for the purpose specified, 100 and means for controlling the admission of the air to and its outlet from said cylinder.

7. A signaling apparatus, comprising a support, an expansible signal connected at one end to one end of the support, an air 105 cylinder carried by the support, a piston working in said cylinder having a piston rod that is connected to the opposite end of said signal, means to supply air under pressure to said cylinder to operate said piston to expand the signal, means for controlling the admission of air to the cylinder, and means for collapsing said signal when pressure upon the piston is released.

In testimony whereof I have hereunto set 115 my hand this first day of July, A. D. 1912.

SLOAN DANENHOWER.
